US0D1022639S

(12) **United States Design Patent** (10) **Patent No.:** **US D1,022,639 S**
(45) **Date of Patent:** **** Apr. 16, 2024**

(54) **RATCHET GEAR**

(71) Applicant: **Hong Ann Tool Industries Co., Ltd.**,
Taichung (TW)

(72) Inventor: **Cheng-Wei Su**, Taichung (TW)

(73) Assignee: **Hong Ann Tool Industries Co., Ltd.**,
Taichung (TW)

(**) Term: **15 Years**

(21) Appl. No.: **29/785,777**

(22) Filed: **May 27, 2021**

(51) LOC (14) Cl. **08-05**

(52) U.S. Cl.

USPC **D8/25**; D8/21

(58) **Field of Classification Search**

USPC D8/25, 21; D15/5

CPC B25B 13/463

See application file for complete search history.

(74) Attorney, Agent, or Firm — Best & Flanagan LLP

(57) **CLAIM**

The ornamental design for a ratchet gear, as shown and described.

DESCRIPTION

FIG. 1 is a perspective view of a ratchet gear showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the ratchet gear in which the design is embodied that are not considered part of the claimed design.

The shaded surfaces and the solid lines represent the claimed portions of the design.

1 Claim, 7 Drawing Sheets
